[57] CLAIM

The ornamental design for an upper housing of a cleaning machine, as shown and described.

DESCRIPTION

FIG. 1 is a front, perspective view of an upper housing of a cleaning machine showing my new design;
FIG. 2 is a front elevational view thereof;
FIG. 3 is a rear elevational view thereof;
FIG. 4 is a left side-elevational view thereof, the right side-elevational view being a mirror image thereof;
FIG. 5 is a top plan view thereof; and,
FIG. 6 is a bottom plan view thereof.
The broken line showing of a cleaning machine base in FIGS. 1-5 is for illustrative purposes only and forms no part of the claimed design.
